US0D1067612S

(12) **United States Design Patent** (10) **Patent No.:** **US D1,067,612 S**
(45) **Date of Patent:** **** Mar. 25, 2025**

(54) **SHOE**

(71) Applicant: **NIKE, Inc.**, Beaverton, OR (US)

(72) Inventor: **Marie Odinot**, Portland, OR (US)

(73) Assignee: **NIKE, Inc.**, Beaverton, OR (US)

(**) Term: **15 Years**

(21) Appl. No.: **29/921,988**

(22) Filed: **Dec. 20, 2023**

(51) **LOC (15) Cl.** **02-04**

(52) **U.S. Cl.**

USPC **D2/972**; D2/947

(58) **Field of Classification Search**

(57) **CLAIM**

The ornamental design for a shoe as shown and described.

DESCRIPTION

FIG. 1 is a side view of a shoe showing my new design; FIG. 2 is a rear perspective view thereof;

FIG. 3 is a rear view thereof;

FIG. 4 is an opposite side rear perspective view thereof; and, FIG. 5 is an opposite side view thereof;

The broken lines immediately adjacent to the shaded area define the bounds of the claimed design and form no part thereof. The broken line showing of the thin rectangular-shaped regions on the lower element form no part of the claimed design. The broken line showing of the region between the upper and lower elements form no part of the claimed design. The broken lines depicting the remainder of the shoe form no part of the claimed design.

1 Claim, 5 Drawing Sheets
